UNITED STATES PATENT OFFICE.

WILLIAM S. PAYNE, OF SHERLOCK, WASHINGTON.

SHIPPING-BOX.

1,140,765.

Specification of Letters Patent. Patented May 25, 1915.

Application filed May 21, 1914. Serial No. 839,929.

To all whom it may concern:

Be it known that I, WILLIAM S. PAYNE, a citizen of the United States, residing at Sherlock, in the county of Thurston and 5 State of Washington, have invented certain new and useful Improvements in Shipping-Boxes, of which the following is a specification.

This invention relates to that class of receptacles known as shipping boxes, and its 10 object is the provision of a box of this character which will be of light and inexpensive construction and which may be readily assembled to afford a strong and comparatively rigid structure.

With these ends in view, the invention 15 consists in a box having an outer wall section and a collapsible inner section interfitting therewith to afford the box-lid and 20 bottom members which overlap the walls of the outer section.

In the drawings, Figure 1 is a perspective 25 view of my improved box in assembled condition and illustrated with the lid tilted up. Fig. 2 is a similar view of the inner section shown detached. Fig. 3 is a transverse vertical section of the box. Fig. 4 is a plan view of the blank such as employed for the inner section.

According to the present invention, a box 30 is comprised of a shell formed of two thin sheets of wood veneering or other suitable material. One of said sheets is of an oblong form and is transversely scored to afford 35 bends at the corner edges 5 of the end walls 6 and side walls 7, and in one of the side walls an overlapping portion 8 which is secured to the juxtaposed wall by fastenings such as staples 9. The other sheet is made 40 from an oblong piece having a width equal to or slightly greater than the external width of the box. This sheet, as shown in Fig. 4, is scored transversely at 10, 10¹ and 10² to afford bends for the corner edges 11 45 between the supplementary end-walls 12, 12¹ and the elements 13 and 14 which respectively serve as the lid and bottom of the box.

The widths of the portions 12, 12¹ of such piece are, however, of widths equal to or slightly less than the distance between the 50 walls 7 of the outer member of the shell.

The members of the box are assembled by inserting the lid 13 through the opening in the outer shell part and then pushing the end 12¹ of the inner part against an end-wall 7 of the outer part. The end portion 12 is then shoved into the opening of the outer box-part and against the other end-wall 7. By thus having the portions 12 and 12¹ juxtaposed with the end-walls 7 of the 60 outer box-part, the bottom 14 is brought against and underlying the lower edges of the side-walls 6, while the lid 13 is hingedly connected at 10 to the portion 12¹ and is adapted to be closed down upon and overlie 65 the upper edges of the side-walls 6, the portion 12 and the end-wall 7 adjacent to the latter.

From the foregoing, it will be understood 70 that the outer wall-part of the box be interposed between the lid and bottom elements, and which, acting in coöperation with the portions 12 and 12¹ of the inner box-part, prevent the box from collapsing or being 75 distorted when in assembled condition.

Having described my invention, what I claim, is—

A two-part box, one of said parts forming the side and outer end walls, and the other part being formed with recessed portions 80 folded and positioned against the inner faces of the outer end walls and also formed with relatively wider portions which serve as the top and bottom walls of the box, said wider portions being adapted to bear against 85 the upper and lower edges of the first-named part.

Signed at Seattle, Wash., this 12th day of May, 1914.

WILLIAM S. PAYNE.
